AMPLIFIER

James W. Conklin, Audubon, N. J., assignor to
 Radio Corporation of America, a corporation of
 Delaware

Application July 31, 1940, Serial No. 348,742

7 Claims. (Cl. 179—171)

My invention relates to television transmitters and particularly to direct current-coupled amplifiers or modulators employed in such transmitters.

In television systems, it is generally preferred that the transmitter be so designed as to transmit the direct current component of the picture signals. This necessitates direct current coupling between the modulator and power amplifier tubes.

The conventional D. C. coupled amplifier requires a biasing source such as a battery above ground potential to keep the amplifier tube grids at the desired negative bias. The use of such a battery is undesirable in transmitters where high voltages and large power outputs are encountered. The capacity to ground of such a battery may cause difficulties also where the transmitter is being operated at a high frequency.

An object of my invention is to provide an improved direct current coupling for electron discharge tubes which does not require a biasing source at a high potential above ground and which does not introduce excessive degeneration at the low frequency signal components.

A further object of my invention is to provide an improved television transmitter of the type which will transmit the direct current component of the picture signal.

A further object of my invention is to provide an improved resistance-coupled amplifier or modulator.

In practicing my invention, according to one preferred embodiment, the plate of a modulator or amplifier tube is coupled through a direct current connection to the control grid or grids of the succeeding amplifier (there being no voltage source in this connection), while the cathode of the modulator tube is operated below ground potential by grounding the positive end of the modulator tube plate supply. Any voltage drop across the plate supply impedance will change the cathode potential with respect to the control grid potential and cause degeneration unless proper steps are taken to prevent it. At the lower frequencies, in the region of 60 cycles, for example, such degeneration may reduce the gain of the modulator tube by one-half.

I avoid such undesired degeneration by making the control grid of the modulator tube change in potential substantially the same amount as and substantially in phase with the cathode potential changes. Thus, the "degenerating voltage" causes no change in the potential of the control

grid with respect to the cathode and it has no degeneration effect.

The grid potential is made to follow the cathode potential by employing a high plate impedance tube such as a tetrode or pentode in the amplifier stage immediately preceding the modulator tube and by connecting the cathode of the modulator tube back to the plate of the high impedance tube, through a condenser and through part of the resistance in the plate circuit of the high impedance tube. As a result, the modulator tube grid is made to follow any variations in cathode potential since the grid is coupled to the said plate. However, since the plate current of a high impedance tube is substantially independent of changes in its plate potential, these voltage variations do not affect the signal output of the high impedance tube and, therefore, do not affect the input signal supplied to the modulator tube.

The invention will be better understood from the following description taken in connection with the accompanying drawings, in which

Figure 1 is a circuit diagram of a television transmitter embodying my invention,

Figure 2 is a circuit diagram of an amplifier or modulator designed in accordance with another embodiment of my invention, and

Figure 3 is a circuit diagram of an amplifier or the like designed in accordance with another embodiment of my invention.

Referring to Fig. 1, my invention is shown applied to a television transmitter of the type wherein the carrier wave is negatively modulated by a composite signal consisting of picture signal and synchronizing pulses.

By negative modulation is meant modulation in such direction that a decrease in light in the picture results in an increase in the carrier wave amplitude. Thus, in the case assumed in this application where synchronizing pulses are in the direction representing black in the signal, these pulses are represented by maximum carrier amplitude.

The transmitter comprises the necessary terminal equipment and amplifiers indicated by the block 10 for supplying the above-mentioned composite signal which is to modulate the transmitted carrier wave. The modulating signal includes regularly recurring line synchronizing pulses, these pulses preferably being set on pedestals, the tops of which reach "black" level. The modulating signal also includes regularly recurring framing pulses.

The terminal equipment 10 may be the same

as that described in Patent 2,192,121, issued February 27, 1940, to A. V. Bedford, and assigned to the Radio Corporation of America. As indicated above, the pedestals appearing in the output of such terminal equipment are caused to go to a fixed level such as black in the picture, whereby the direct current component of the picture signal may be reinserted after the signal has passed through alternating current amplifiers.

The terminal equipment 10, if preferred, may be substantially the same as that shown in Vance Patent 2,187,039, issued November 15, 1938, and assigned to the Radio Corporation of America. In the Vance patent, peaks of the synchronizing pulses go to black or to a fixed level beyond black.

The modulating signal is amplified by a suitable amplifier 11 and supplied to the control grid of a modulator tube 12 with the synchronizing pulses of negative polarity. The plate circuit of the modulator tube 12 is direct current-coupled to a power amplifier 13 for modulating the radio frequency carrier supplied from a suitable carrier wave source 14.

The power amplifier 13 comprises the amplifier tubes 16 and 17 which have a certain output rating determined by the plate dissipation.

It will be noted that the direct current connection between the plate of the modulator tube 12 and the control grids of the power amplifier tubes 16 and 17 does not contain any source of biasing potential such as a battery. A conventional D. C. coupled amplifier, of course, includes in this connection a battery or the like to maintain the control grids of the power amplifier tubes at the desired bias potential. Such a battery necessarily is above ground potential and obviously is undesirable in a high power, high frequency transmitter.

In accordance with one feature of my invention, the plate of the modulator tube 12 is operated near ground potential, the cathode of this tube being at a high voltage below ground potential. The plate supply for the modulator tube is indicated at 19, this plate supply preferably being of the usual rectifier-filter type supplied from the 60-cycle power line and having the usual voltage divider 21 connected thereacross.

The positive side of the voltage supply 19 is connected to ground and is also connected through a comparatively low impedance resistor 22 to the plate of the modulator tube 12. The resistance value of resistor 22 is so selected as to apply the desired negative bias potential to the control grids of the power amplifier tubes 16 and 17. As will be explained later, the voltage drop across resistor 22 also supplies the desired bias or reference voltage for a diode 23 comprising part of a direct current reinserting circuit which preferably is included in the transmitter. This D. C. reinserting circuit is described and claimed in my copending application Serial No. 348,743, filed July 31, 1940, entitled "Direct current restoring apparatus," and assigned to the Radio Corporation of America.

The negative terminal of the voltage supply 19 is connected through a conductor 24 to the cathode of the modulator tube 12. Where the modulator tube is of the screen grid type, the screen grid is connected to a suitable positive point on the voltage divider 21 as illustrated.

Referring now to the input circuit of the modulator tube 12, and to the preceding amplifier tube 11 which supplies picture signal and synchronizing pulses to this input circuit, the amplifier tube 11 is of the high impedance type such as a tetrode

or a pentode whereby changes in its plate voltage will not noticeably affect its current output. A suitable operating voltage is applied to the plate of the tube 11 through a comparatively high impedance resistor 25, a comparatively low impedance resistor 27, and, if desired, an inductance or peaking coil 28 for holding up the high frequency response of the amplifier.

The plate circuit of the tube 11 is connected through a coupling condenser 29 to the input circuit of the modulator tube 12.

In the specific application here described in which the D. C. reinserting circuit covered by my above-mentioned copending application is included in the transmitter circuit, the desired negative bias for the control grid of the modulator tube 12 is applied through a grid leak resistor 31 from a section X of a voltage divider 32 and from an integrating circuit 33 in series therewith. The grid circuit of the modulator tube may be traced from the cathode of the modulator tube 12 through the conductor 24 to the integrating circuit 33 and through the integrating circuit and the section X of the voltage divider 32 to the grid leak resistor 31 and to the control grid of the modulator tube.

It will be apparent that the voltage divider section X applies a negative bias to the modulator tube grid while the voltage drop across the integrating circuit 33 opposes this negative bias and, as will be explained hereinafter, reduces it by an amount depending upon the magnitude of the synchronizing pulse peaks which are passed by the reference level setting diode 23 described hereinabove. It is, of course, this variation in the bias applied to the modulator tube that varies the D. C. output of the modulator tube to give the desired D. C. insertion.

As previously indicated, one of the main objects of the present invention is to avoid any substantial amount of degeneration which might be introduced because of the impedance of the plate supply 19 (and voltage divider 21) of the modulator tube. It will be understood that, at the lower frequencies, this impedance may be of substantial magnitude even though large bypass condensers have been used, such bypass condensers being included in the circuit represented by the block 19. As previously stated, such impedance will cause a degenerative action, in the absence of means to prevent it, as a result of the voltage drop thereacross varying the potential of the modulator tube cathode with respect to ground and thus varying the potential difference between the control grid and the cathode of the modulator tube.

I prevent such a variation in potential difference by connecting the cathode of the modulator tube 12 through a large capacity condenser 36 to the junction point of the resistors 26 and 27. Thus the cathode of tube 12 is coupled through the plate resistor 27 to the plate of amplifier 11 and through the coupling condenser 29 to the grid of the modulator tube 12. Now, so far as voltage drop across the impedance of the plate supply 19-21 is concerned, the control grid and the cathode of tube 12 are tied together whereby the grid will follow any changes in cathode potential. The result is that the variations in cathode potential do not cause degenerative feedback.

Since the amplifier tube 11 is of the high impedance type, the voltage variations impressed upon its plate through the condenser 36 will not cause any variations in the plate current through

the plate resistors 26 and 27. It is important that there be no substantial variation in this plate current as a result of the potential variations of the modulator tube cathode, as otherwise there would be introduced a voltage drop across the resistor 27 which would be applied to the control grid of the modulator tube.

It may be noted that the low frequency components which might introduce a large amount of degenerative feedback may be of the order of 60 cycles and may represent the fundamental frequency of the vertical synchronizing pulses, for example, or they may be ripple voltages due to imperfect filtering in the plate supply.

The present invention does not necessarily include the D. C. restoring circuit, but, in the particular example being described, the direct current connection between the modulator tube and the power amplifier is used because it is desired to transmit the D. C. component of the picture signal, and this preferably is accomplished by utilizing the D. C. restoring circuit described and claimed in my above-mentioned copending application. As previously stated, it includes the diode 23, which is biased to the desired reference voltage to permit only the peaks of the synchronizing pulses to pass therethrough and produce a voltage drop across a resistor 31 in series with the diode 23 when the peaks exceed the said reference voltage. The reference voltage level is set to the proper value by adjusting a tap 38 on the voltage divider 21, the voltage between the tap 38 and the positive end of the voltage divider 21 being less than and in opposition to the voltage drop across resistor 22.

The synchronizing pulse peaks appearing across the resistor 31 are fed through a coupling condenser 39 to the grid of an amplifier or control tube 41, which preferably is biased substantially to cut-off, whereby pulses of current flow through the plate circuit of tube 41 to build up the previously mentioned bias control voltage across the integrating circuit 33. The plate circuit of the control tube 41 may be traced from its plate through the conductor 24 to the integrating circuit 33 and through the integrating circuit and a portion of the voltage divider 32 to the cathode of the control tube.

The integrating circuit 33 comprises a resistor 42 and a condenser 43 having such resistance and capacitive value that the charge applied to the condenser 43 (as a result of the peaks of the synchronizing pulses reaching the grid of the control tube 41) will hold over for several successive line synchronizing pulses. This time constant, in other words, is similar to the time constant employed in other D. C. inserting circuits.

The voltage divider 32 is connected across a suitable voltage supply 46, such as a battery or the usual rectifier-filter supply unit. It will be noted that the voltage drop across the section X of the voltage divider 32 applies a negative bias to the grid of the modulator tube 12. The voltage divider 32 also supplies the plate voltage and the grid bias voltage for the control tube 41, the grid bias preferably being sufficient to bias tube 41 substantially to cut-off.

An adjustable tap 47 on the voltage divider 32 is adjusted to a point where the value of the modulator tube bias insures that the signal peaks (in this case, the synchronizing pulse peaks), at least, will pass through the modulator tube 12 under all signal conditions so long as synchronizing pulses are being supplied from the generator 10 whereby the signal peaks in the mod-

ulator tube output will just exceed the reference voltage. At all times, therefore, a voltage will be fed back to establish the desired equilibrium condition. This bias adjustment, for example, may be such that, in the absence of a modulating signal, the modulator tube 12 is biased to hold the carrier wave at an amplitude representing "black" in the picture.

In Fig. 2, there is shown an embodiment of my invention in which undesired degeneration resulting from the use of self-biasing is avoided. Referring to Fig. 2, there is shown an amplifier comprising an amplifier tube 51 of the high impedance type which is resistance-coupled to a second amplifier tube 52 by means of plate resistors 53 and 54 in the plate circuit of the first tube and by means of a coupling condenser 56.

The plate of the amplifier tube 52 is supplied through a plate resistor 57 with an operating potential from a suitable voltage supply 58 having a voltage divider 59 connected thereacross.

The desired negative bias for the control grid of the second tube is provided by means of a cathode resistor 61 shunted by a condenser 62, the lower end of the cathode resistor 61 being connected to ground. In this embodiment, the negative terminal of the plate voltage supply 58 is connected to the grounded end of the cathode resistor 61. The voltage drop appearing across the cathode resistor 61 is applied to the control grid of the second tube through a grid leak resistor 63.

As is well known in the art, the above-described self-biasing circuit 61-62 introduces a certain amount of degeneration at the lower frequencies. I avoid substantially all of this degeneration by coupling the cathode of the second tube to its control grid through a condenser 64, through the plate resistor section 54 of the high impedance tube 51 and through the coupling condenser 56. Thus, as previously described, the control grid of tube 52 is made to follow any potential variations of its cathode due to the impedance presented to the lower frequencies by the cathode self-biasing circuit 61-62.

In Fig. 3, there is illustrated another embodiment of my invention as applied to an amplifier feeding into a coaxial cable or the like. The amplifier comprises a high impedance amplifier tube 66 which is resistance-coupled to a second amplifier tube 67 by means of plate resistors 68 and 69 and a coupling condenser 71.

In this embodiment, the plate of the second tube is operated at substantially ground potential, the plate supply, such as the battery 72, having its positive side connected to ground and to the plate of the second tube through a comparatively low impedance output resistor 73.

The coaxial cable 74, comprising an inner conductor 76 and an outer grounded conductor 77, preferably is properly terminated as by means of a resistor 78 of suitable value. It will be evident that, with this arrangement, there is no high voltage difference between the central conductor 76 and the outer conductor 77 of the cable. Therefore, there is no danger of voltage breakdown in the cable.

Since in this embodiment of the invention, as in the first-described embodiment, the cathode of the amplifier tube 67 is being operated below ground potential, there might be serious degeneration at the lower frequencies because of the unavoidable plate supply impedance. Such degeneration is avoided in the manner previously

described by coupling a condenser 79 between this cathode and the junction point of the plate resistors 68 and 69 of the high impedance tube 66.

From the foregoing, it will be apparent that I have provided a simple and effective circuit for operating an amplifier or modulator tube with its output electrode at or near ground potential without introducing undesirable degeneration. It will also be apparent that I have provided an improved television transmitter so designed as to transmit the direct current component of a picture signal without the use of biasing batteries or the like above ground potential.

I claim as my invention:

1. An amplifier comprising a first amplifier tube and a second amplifier tube which are impedance-coupled, each of said tubes having a plate electrode, a control grid and a cathode, means for operating said second tube with its cathode substantially below ground potential, and means for coupling the cathode of said second tube to its control grid through a portion of the coupling impedance in the plate circuit of said first tube.

2. The invention according to claim 1 wherein the first amplifier tube is of the high plate impedance type.

3. An amplifier comprising a first amplifier tube and a second amplifier tube which are resistance-coupled, each of said tubes having a plate electrode, a control grid and a cathode, means for operating the plate electrode of said second tube at a potential nearer ground than the potential of its cathode, and means for coupling the cathode of said second tube to its control grid through a portion of the coupling impedance in the plate circuit of said first tube.

4. The invention according to claim 3 wherein the first amplifier tube is of the high plate impedance type.

5. In combination, a high plate impedance amplifier tube, a second amplifier tube, each of said tubes having a plate, a control grid and a cathode, means for coupling said tubes, said means comprising a plate resistor for said first tube and

a coupling condenser connected between the plate of the first tube and the control grid of the second tube, means for operating the second tube with its cathode below ground, and a condenser connected between the cathode of said second tube and a point on said plate resistor whereby the cathode and control grid of the second tube are connected together through at least a portion of said plate resistor.

6. In combination, a high plate impedance amplifier tube, a second amplifier tube, each of said tubes having a plate, a control grid and a cathode, means for coupling said tubes, said means comprising a low impedance resistor and a comparatively high impedance resistor connected in series in the plate circuit of the first tube with the low impedance resistor adjacent to its plate and a coupling condenser connected between the plate of the first tube and the control grid of the second tube, means for operating the second tube with its cathode below ground, and a condenser connected between the cathode of said second tube and the junction point of said two resistors whereby the cathode and control grid of the second tube are connected together through the low impedance resistor.

7. In combination, a high plate impedance amplifier tube, a modulator tube and a radio frequency amplifier tube, each of said tubes having a plate, a control grid and a cathode, a direct current connection between said modulator tube and said radio frequency amplifier, a voltage supply for said modulator tube connected between its plate and its cathode with the positive side of said supply connected to ground, means including a plate resistor in the high impedance tube plate circuit for coupling said high impedance tube to said modulator tube, and a condenser connected between the cathode of the modulator tube and a point on said plate resistor whereby the cathode and control grid of the modulator tube are connected together through at least a portion of said plate resistor.

JAMES W. CONKLIN.
